UNITED STATES PATENT OFFICE.

GUSTAV HILGENSTOCK, OF DAHLHAUSEN, GERMANY, ASSIGNOR TO THE UNITED COKE AND GAS COMPANY, OF PHILADELPHIA, PENNSYLVANIA.

APPARATUS FOR LEVELING COAL IN COKE-OVENS.

SPECIFICATION forming part of Letters Patent No. 639,570, dated December 19, 1899.

Application filed March 7, 1898. Serial No. 672,839. (No model.)

To all whom it may concern:

Be it known that I, GUSTAV HILGENSTOCK, a subject of the King of Prussia, German Emperor, residing at Dahlhausen-on-the-Ruhr, 5 Kingdom of Prussia, Germany, have invented certain new and useful Improvements in Apparatus for Leveling Coal in Coke-Ovens, of which the following is a full and accurate specification, reference being had to the drawings, forming a part thereof.

My invention relates to apparatus for leveling and consolidating the coal dumped through the charging-chutes into the coke-ovens and which, owing to the manner of 15 charging the ovens, forms itself into conical heaps. Heretofore this work has generally been accomplished by workmen operating leveling-rakes; and the object of my invention is to provide a simple and efficient apparatus by which this work can be more expeditiously performed and with better results.

The nature of my improvements will be best understood as described in connection with the drawings, in which they are illustrated, 25 and in which—

Figure 1 is a side elevation showing my leveling device mounted, as it conveniently is, on the same truck with the coke-discharging apparatus. Fig. 2 is a plan view of my machine. Fig. 3 is a side elevation, on a larger scale, of the portion of my apparatus which acts upon the coal. Fig. 4 is a plan view of the portion of the apparatus shown in Fig. 3. Fig. 5 is a sectional view taken through the 35 top of the coke-oven and through my leveling apparatus, the section being taken on the line 55 of Fig. 4. Fig. 6 is a sectional view of the leveling apparatus, taken as on the line 66 of Fig. 4. Fig. 7 is a view indicating a simple device by which a reengagement of parts 40 may be made at a certain stage in the operation of my device.

l', Figs. 1 and 2, indicates the coking-oven, the coal being represented in sloping heaps, 45 as it naturally forms itself when charged through the openings ll'.

oo indicate tracks running in front of a row of coking-ovens l', n³ indicating the wheels of a truck, the frame of which is indicated at 50 n and which may be the usual form of truck

supporting a coke-discharging device such as is indicated at q.

n¹ and n² indicate the framing supported on the truck and upon which my leveling apparatus is supported.

m indicates a motor supported on the truck and by means of which my apparatus is actuated.

t indicates what I call the "carrying-rod" of my apparatus. It is conveniently made up, 60 as shown, of two iron plates t' t', (see Fig. 6,) secured together at top and to a bar t² at bottom, said bar being provided on its under side with a rack, (indicated at z.) This carrying-bar is supported in a horizontal position 65 on bearings which permit it to move freely in the direction of its length. As shown, these bearings consist of rolls r r', which serve both to guide and support the bar.

d, d, &c., are grooved guide-rollers journaled on pins d', secured to the carrying-bar t and arranged, preferably in pairs, as shown, so as to engage both the top and bottom of the shovel-carrying rods, which are indicated at a a. One of these rods a is supported on 70 each side of the carrying-bar t, and to each of them is secured a series of clamps, (indicated at f²,) which support the shovels, (indicated at f and f³.) In the case of the shovels f the clamps f² support directly-pivoted 75 pins, (indicated at f',) upon which the shovel-blades f are pivoted so as to turn upward freely in one direction, while their motion in the other direction is prevented by means of a stop-lug, such as f⁴, projecting from the clamp f². The other shovel-blades (indicated at f³) are securely fastened to the clamps and only move with them.

c c indicate pivot-pins secured to the bars a near their rear ends and to which are connected the ends of connecting-rods s s, the other ends of which are pivotally connected with crank-pins extending out from the face of wheels or disks, as indicated at k, and preferably adjustable therein, as by means of 90 slots k'. The wheels k are journaled, as indicated, at or near the end of the carrying-rod t, and it will be obvious that when the wheels k are rotated the rods a will be reciprocated in the bearing-rolls d.

z^4 is a gear-wheel supported on the frame n' and lying directly beneath and in position to engage with the bar t^2 and its rack z . The gear-wheel z^4 is driven through the gear-wheel z^5 , in turn actuated by the gear z^3 , secured to the same axle with the gear-wheel z^2 , which is driven by a gear z' , actuated by a crank driven from the motor m . The crank and wheel shaft has also connected to it, as shown in dotted lines, a friction-wheel, (indicated at h' in Fig. 1,) which in turn drives a smaller gear-wheel h , the function of which is, when the parts are in the position shown in Fig. 1, to come in contact with and drive the wheels k k ; but these wheels may obviously be driven by hand or in any other convenient manner.

g g indicate rollers journaled on a shaft g' , which is supported at the end of the carrying-bar t on bracketed arms g^2 .

t^4 , Fig. 7, indicates a recess formed in the under side of the bar t^2 , in which is situated a pivot-pin p , having depending from it a tooth p' , which is free to move upward and forward, but is prevented from moving backward by means of a stop p^2 .

p^3 indicates a lug or projection from the gear-wheel z^4 , which when the parts are as shown in Fig. 1 will come in contact with the pivoted tooth p' as the gear-wheel revolves. As long as the gear-wheel is revolving in a forward direction or to the right, as shown in Fig. 1, its lug p^3 will simply raise the tooth p' at each revolution. As soon as the motion of the gear-wheel is reversed, however, it engages the tooth p' and forces the carrying-bar t backward, so as to engage the gear-wheel z^4 with the rack z .

In moving my apparatus around on the truck it is retracted to about the position indicated in dotted lines in Fig. 1, being brought to register with the open end of an oven which is being filled. The motor m is set in operation, so as to drive the gear-wheel z^4 in a forward or right-hand direction. This gear being engaged with the rack z , the carrying-bar t is rapidly forced outward or forward into the oven until it reaches the position indicated in Fig. 1. Just before reaching this position the gear-wheel z^4 has left contact with the rack z , and the carrying-bar comes to a standstill, with its wheels k in contact with the friction-wheel h , which at once causes them to revolve and begins the work of reciprocating the shovel-carrying rods a a . This causes the shovels f and f^3 to move to and fro over the top of the fuel, pushing away and leveling down the tops of the cones and bringing the contents of the oven to a dead-level. I have found it advantageous to make some of the shovels, as indicated at f^3 , stationary with regard to their position on the rods a , and those indicated at f movable on the pivot-pins f' , but movable only in one direction, 65 the stops f^4 preventing them from moving in

the other direction. After the fuel in the oven is leveled off I reverse the motor, driving the gear-wheel z^4 backward or toward the left and reengaging it with the rack z , either by the automatically-acting device indicated in Fig. 7 or any other convenient mechanism, or even by drawing the carrying-bar backward by hand. The carrying-bar, with its attachments, is then readily withdrawn from the oven, the rollers passing down upon and compacting the fuel as they pass over its top.

Having now described my invention, what I claim as new, and desire to secure by Letters Patent, is—

1. In an apparatus for the leveling of the coal in a coke-oven the combination with a carrier-rod adapted to be thrust into the oven, of shovels supported upon said rod and adapted to be moved along the same, and means 85 for giving said shovels a reciprocating movement in the oven and along the rod, substantially as described.

2. In an apparatus for the leveling of the coal in a coke-oven, the combination with a carrier-rod adapted to be thrust into the oven, of shovels supported upon said rod and adapted to be moved along the same, a roller attached to the end of the said carrier-rod, and means for giving said shovel a reciprocating 95 movement in the oven and along the rod, substantially as described.

3. In an apparatus for the leveling of the coal in a coke-oven, the combination with a carrier-rod adapted to be thrust into the oven, 100 of another rod or rods supported by said carrier-rod and adapted to be moved along the same, shovels secured to said relatively movable rod or rods, a crank supported by the rear end of the said carrier-rod and connected 105 to the said relatively movable rod or rods, and means for rotating said crank to reciprocate the shovels, substantially as described.

4. In an apparatus for the leveling of the coal in a coke-oven, the combination with a carrier-rod adapted to be thrust into the oven, and forming in part a rack, of a pinion gearing with said rack, another rod or rods supported by said former rod and adapted to be moved along the same, shovels secured to said 115 relatively movable rod or rods, a crank-disk supported by the exterior end of the said carrier-rod and connected to said relatively movable rod or rods, a friction-disk located in the path of said crank-disk, and means for operating said friction-disk as well as said rack-actuating pinion, the length of the rack and the position of the pinion, the friction-disk and the crank-disk being such that the rack disengages from the pinion and the crank-disk engages with the friction-disk on the carrier-rod having finished its inward stroke, substantially as described.

5. In a coke-oven, the combination with machinery for discharging the coke, of an ap- 130

paratus for leveling the coal in the oven, said apparatus consisting of a carrier-rod adapted to be thrust into the oven, shovels arranged upon said rod and adapted to be moved along the same, and means for reciprocating the shovels along the carrier-rod, substantially as described.

In witness whereof I have hereunto set my hand in presence of two witnesses.

GUSTAV HILGENSTOCK.
